UNITED STATES PATENT OFFICE.

HERVEY DEXTER THATCHER, OF POTSDAM, NEW YORK.

BOTTLE OR CONTAINER.

No. 891,879.

Specification of Letters Patent.

Patented June 30, 1908.

Application filed October 21, 1907. Serial No. 398,385.

To all whom it may concern:

Be it known that I, HERVEY DEXTER THATCHER, a citizen of the United States, residing at Potsdam, in the county of St. Lawrence, State of New York, have invented certain new and useful Improvements in Bottles or Containers, of which the following is a description, reference being had to the accompanying drawing, and to the letters and figures of reference marked thereon.

My invention relates to improvements in bottles or containers and more especially to structures of this character which are constructed in whole or in part of paper or other fibrous material, and designed to be used but a single time.

The invention set forth herein is an improvement upon the devices shown and described in my prior applications Serial Numbers 363,216, filed March 21, 1907, and 382,065 filed July 3, 1907.

The object of my invention is to provide a container formed of paper or other fibrous material which may be manufactured in an expeditious and economical manner and which is thoroughly sanitary and free from bacteria and which container is also moisture proof, so that the same may be submerged in or surrounded by a refrigerant.

A further object of my invention is to provide a container which may be readily filled and closed for delivery and which shall have a separate opening for the discharge of its contents, the separate opening being provided with a covering means which must be destroyed in order to get at the contents, thus rendering the container capable of only a single use.

Further objects of my invention will in part be obvious and will in part be herein-after more fully described.

In the drawings which show by way of illustration one embodiment of my invention: Figure 1 is a top plan view of the outer heavy disk, forming one member of the closing head. Fig. 2 is a top plan view of the inner flexible disk, forming the other member of the closing head. Fig. 3 shows a heavy disk superposed upon the flexible disk in position for entrance into the open end of the tubular body to form the closing head. Fig. 4 is a section through my improved container in its completed form.

In the drawings the body 1 of my improved container is shown as of tubular form

and the same is preferably made of paper pulp board or other similar fibrous material. In the construction of the same, the material is cut into a sheet of proper size to form a tube of the desired dimensions, and such sheet is then folded into tubular form and its meeting edges secured in any suitable manner. The container is then completed by the insertion of the closing head. The lower closing head comprises a heavy disk 2, which is slightly less in diameter than the inner diameter of the tube and a flexible disk 3, which is considerably larger in diameter than the heavy disk 2. The heavy disk is laid upon the flexible disk and as said disk are crowded into the tubular body portion the flexible disk is drawn between the inner surfaces of the tubular body and the outer edge of the heavy disk. The upper closing head comprises a heavy disk 5, which is also of a slightly less diameter than the inner surface of the tubular body and a flexible disk 6, which is of considerably larger diameter than the heavy disk.

The heavy disk is superposed upon the flexible disk as shown in Fig. 3 and said disks are then inserted in the upper open end of the tubular body portion. As said disks are crowded into the tubular body portion, the flexible disk will be drawn between the outer edge of the heavy disk and the inner surface of the tubular body. The heavy disk of both closing heads is preferably coated with glue, paste or cement, so that the same is secured firmly to the lighter flexible disk. As shown in Fig. 1, the heavy disk 5, is provided with a central opening or aperture 7, and at one side thereof, is a second opening or aperture 8, which is preferably substantially semicircular in outline. On the opposite side of the opening 7 is a small preferably round opening 9. The central opening 7 is cut through the flexible disk and said opening is closed by a suitable cover 10, which as shown in Fig. 4, is provided with a flange 11 resting upon the outer disk and preventing the cover from being pushed into the receptacle. Said cover is preferably provided with a staple which is driven into the same, but does not extend in through the inner surface. Said staple forms a suitable means for withdrawing the cover 10 by the aid of a hook or other instrument which may be slipped into the staple for lifting the cover.

After the container has been formed in the

manner described, the same is dipped into a body of molten paraffin which coats the entire inner surface thereof and which also may coat the entire outer surface. The cover 10 5 may be coated with beeswax or the like so as to fit snugly the opening in the disk 5, and after the container has been paraffined, both inside and out to render it waterproof and sterile, the cover or stopper 10 is then inserted 10 in the opening to keep the container sterile until used.

The operation of my device will be apparent from the above description. When it is desired to use the container, the cover 10 is 15 withdrawn and the container filled through the central opening after which the cover is inserted, which closes the container and prevents the contents from being exposed to the air. A closing cap 13 may then be placed 20 over the end of the container if desired, and the container is delivered in this condition.

When it is desired to use the contents of the container, the inner flexible disk covering the opening 8 is broken or cut by a suitable implement. Said inner flexible disk being coated with paraffin, may be easily cut and the portion thereof which covers the opening 8, removed. This opening 8 is made 25 in the form of a semicircle so as to readily receive a spoon or other similar shaped implement if desired. The contents of the container may be delivered through the opening 8. If it is desired to have the milk or other material contained in the container flow 30 freely and without regurgitation, the inner disk covering the opening 9, is punctured to admit the air.

It will be readily seen that by my form of construction, wherein the inner disk is destroyed 40 in order to properly deliver the contents of the container, said container is thereby mutilated and cannot be refilled and sold as originally.

Where the central opening in the container 45 is used for both filling the container and delivering the contents thereof, considerable inconvenience follows for the reason that the material cannot be readily delivered through the central opening. On the other hand, 50 where an opening is formed in the closing head at one side of the center and used for filling and delivering, great inconvenience arises from the filling, for the reason that great care must be exercised in order to 55 properly position the container in the filling machine. By my device however, where the filling is accomplished through the central opening and the delivering through an opening at one side, all the above objections are 60 overcome, and I have thus provided a container which may be very readily and easily filled and which is also very convenient when being emptied. Furthermore, as above noted by the present construction wherein it is 65 necessary to destroy a portion of the closing

head in order to properly deliver the contents of the container, I have provided a container which may be used only a single time.

Having thus particularly described my invention, what I claim as new and desire to 70 secure by Letters Patent, is:

1. A container comprising a tubular body formed of fibrous material, closing heads fitting inside of the outer ends of said tubular body, one of said closing heads having an 75 opening centrally thereof, a cover or stopper fitting said opening, said closing head having a delivery opening therein at one side of the central filling opening and a vent opening on the opposite side of said central opening, and 80 means for closing said delivery and vent openings, said container being coated interiorly with a moisture-proof substance.

2. A container comprising a tubular body formed of fibrous material, closing heads 85 thereof, which include an outer disk and an inner flexible disk, said outer disk having an opening therein extending through said flexible disk, a cover for said opening, said outer disk having a delivering opening therein at 90 one side of said filling opening which delivery opening is normally closed by the inner flexible disk.

3. A container comprising a tubular body formed of fibrous material, closing heads 95 located in each end of said tubular body, one of said closing heads comprising an outer heavy disk and an inner flexible disk extending beyond the edge of the outer disk, said heavy disk having an opening centrally 100 thereof, which passes through said flexible disk, said heavy disk having a delivering opening at one side of said central opening and a vent opening at the opposite side of said central opening, said delivering and vent 105 openings being normally closed by the inner flexible disk, and a cover for said central opening.

4. A container comprising a tubular body formed of fibrous material, closing heads 110 located in each end of said tubular body, one of said closing heads comprising an outer heavy disk and an inner flexible disk extending beyond the edge of the outer disk, said heavy disk having an opening centrally there- 115 of which passes through said flexible disk, and said heavy disk having a delivery opening at one side of said central opening and a vent opening at the opposite side of said central opening, said delivering and vent open- 120 ings being normally closed by the inner flexible disk and a cover for said central opening, said container being coated interiorly with a moisture proof substance.

5. A container comprising a tubular body 125 formed of fibrous material, closing heads located in each end of said tubular body, one of said closing heads comprising an outer heavy disk and an inner flexible disk extending beyond the edge of the outer disk, said 130

heavy disk having an opening centrally thereof, which passes through said flexible disk and said heavy disk, a delivering opening at one side of said central opening, and
5 a vent opening at the opposite side of said central opening, said delivering and vent openings being normally closed by the inner flexible disk, a cover for said central opening, said container being coated interiorly with

a moisture proof substance, and a cap for closing the outer end of said container.

In testimony whereof I affix my signature, in presence of two witnesses.

HERVEY DEXTER THATCHER.
